Primary Examiner — Susan E Krakower*Assistant Examiner* — Jerry Hsu(57) **CLAIM**

The ornamental design for a vehicle mirror, as shown and described.

DESCRIPTION

FIG. 1 is a top perspective view of a vehicle mirror, showing our new design, it is understood that the opposite side vehicle mirror is a mirror image thereof;

FIG. 2 is a bottom perspective view thereof;

FIG. 3 is a top rear perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

Any broken lines represent an internal boundary of the design; the line itself and the area within form no part of the claim.
